WASHING MACHINE

Hugo Werner Geschka and Josef L. Gillessen, Dusseldorf, Germany, assignors to Maschinenfabrik Peter Pfeiffenberger G.m.b.H., Dusseldorf-Oberkassel, Germany
Original application Oct. 12, 1959, Ser. No. 845,681.
Divided and this application Sept. 6, 1962, Ser. No. 227,968

8 Claims. (Cl. 68—16)

Washing processes carried out in automatic washing machines are known in which water is continuously supplied to the washing liquid in the washing container of the machine while at the same time an equal quantity of liquid is removed from the container through an overflow. Such processes are disclosed in commonly assigned copending application Ser. Nos. 764,419, now Patent No. 3,071,432, and 834,292 and application Ser. No. 845,681 and now abandoned of which present application is a division. In this manner the dirt detached from the material being washed is continuously removed from the container with the upper layer of washing liquid which is continuously being run off. In order to keep the consumption of washing agent and heat as low as possible, the quantity of water which is continuously added and removed should not be too great. 0.08 to 0.15 litre per minute and per kilogram of dry material to be washed is considered to be a suitable quantity for this purpose. Since in this process a considerable proportion of the dirt is removed relatively early from the container after detachment from the material, the number of separate washing stages can be reduced without impairing the washing effect, and an economical method of washing can thereby be achieved. The so-called degree of whiteness, however, which is an indication of well cared for washing, is not as great as would be expected.

In order to overcome this difficulty, according to the invention described in application No. 764,419, the washing operation is carried out in two stages, during the first of which a continuous supply and discharge of water takes place to and from the washing container and the washing liquid in the container is heated and during the second of which the supply and discharge of water is discontinued but heating is maintained until the end of the washing process. This results not only in a considerable saving in heat and washing agent but also gives the desired greater degree of whiteness.

By far the greatest proportion of the dirt which becomes detached from the material being washed enters the washing liquid at an early stage, when the temperature is still fairly low, and is removed from the container with the water flowing off. In the second stage, only comparatively minor residues of dirt are left in the washing. These are then easily removed by the static washing liquid, which heats up more rapidly, so that the desired degree of whiteness is achieved.

It is here that the principle of the present invention comes into play. It is based on the following consideration: if one operates with a small liquid ratio, i.e. with a small quantity of washing liquid per kilogram of dry material being washed, the heating of the washing liquid in the second stage, in which the water supply and discharge is discontinued, to the desired temperature, e.g. 90° C., can be carried out more rapidly and with less consumption of heat energy. A small liquid ratio is therefore desirable, this ratio varying with the nature of the material being washed and the extent to which it is soiled. On the other hand, if a small quantity of liquid is used, the upper layers of the water will contain a correspondingly greater concentration of dirt. This can be countered, however, by increasing the amount of water

2

continuously supplied and discharged in the first washing stage.

Accordingly, as a further development of the process described in Application No. 764,419 it is now proposed 5 to use an adjustable quantity of liquid in the container and to adapt the rate of continuous supply and discharge of water to the quantity of liquid in the container in each case.

It is, therefore, the principal object of the present invention to provide a novel washing machine in which this process can be carried out efficiently and more or less automatically.

According to the present invention, in the process described above with reference to application No. 764,419 15 the volume of water held by the container is adjustable but the total volume of water supplied to and discharged from the container in the first stage and remaining in the container in the second stage is between 4.4 and 5.5 litres per kilogram of dry material washed. Preferably 20 a total of 5.0 litres of water are used per kilogram of dry material to be washed. Preferably, between 2.7 and 3.8 litres per kilogram of dry material of washing is used for filling the container and a constant amount of 0.14 to 0.05 litre of water per kilogram of dry material per minute 25 is supplied and discharged in the first stage. It has been found that really satisfactory washing results can be obtained only if the quantity of water used for filling the container is kept within the limits given above when using the process of the invention. The figures show that it is 30 possible to obtain a satisfactory result with a smaller quantity than would hitherto have been considered possible provided the rate of constant supply and discharge of water is adjusted accordingly.

The invention is described below with reference to a 35 number of examples:

If the container contains 3 litres of water per kilogram of dry material to be washed and the total quantity of water used in the first phase, which lasts for example 20 40 minutes, is 5 litres, then the quantity of fresh water which must be supplied per minute and per kilogram of dry material is $2:20=0.1$ litres. With the same total quantity of water and the same duration of the first washing stage but with 4 kilograms of water per kilogram of dry material, only 0.05 litre of fresh water are added and removed per minute and per kilogram of dry material. If 45 the total quantity of water to be used in the first stage is 4.6 litres per kilogram of dry material, and if the water level in the container is adjusted so that the container contains 3.5 litres per kilogram of dry material, then, if 50 the first stage is to last 15 minutes, the quantity of water supplied and discharged per minute is $1.1:15=0.073$ litres per kilogram of dry material.

As already mentioned above, a saving in heat can be 55 obtained by reducing the level to which the container is filled in the second stage. As the total quantity of water supplied to and partially removed again from the container during the first stage is constant, and the heat removed in this stage is practically negligible, one can assume 60 the quantity of heat used to be practically the same, regardless of the quantity of water required in each case for filling the container. A considerable difference regarding the heat energy to be consumed occurs in the second stage, however, which is carried out with the water 65 supply and discharge cut off. In this stage, the consumption of heat is approximately proportional to the volume in the container assuming the final temperature is always the same, for example 90° C. If, therefore, the supply of electricity to a washing machine adjusted, for example, to a liquid ratio of 4:1 is 0.7 kw. per kilogram of dry material, then if the washing machine is readjusted to a

liquid ratio of 3:1, the supply would drop to 0.54 kw. per kilogram of dry material.

An automatic washing machine suitable for carrying out this process has, like the machine described in application No. 764,419 a water inlet and an outlet leading to the container and controlled by a regulating valve. The water outlet is adjustable in height and the regulating valve in the water inlet is controlled in dependence on the height adjustment of the overflow.

Further features of the invention will be described by way of example with reference to the accompanying drawings, in which:

FIGURE 1 shows a graph to explain the process; and

FIGURE 2 is a diagrammatic illustration of a washing machine according to the invention.

In the graph shown in FIGURE 1, the time t is shown as the abscissa and the temperature T of the washing liquid is shown as the ordinate. When the washing container has been filled with a quantity of water corresponding to the adjusted level of the outlet the first washing stage begins at the point P_1 . A certain quantity of water is supplied continuously. An equal quantity is removed through the outlet or overflow of the machine. At the same time, the heater is switched on. The temperature of the water rises steadily but not quite linearly up to the point P_2 . This temperature rise during the time t_1 is indicated by the part 1 of the graph. Since, the total quantity of water used during this time is constant, the change in the gradient of the part 1 of the graph is so slight, when the limits given above are observed, that it may be neglected. At the point in time P_2 , when the constant supply and discharge of water is stopped, the first washing stage is completed. In this stage, which may be termed the preliminary wash, the coarse dirt is removed through the overflow along with the constantly discharged water. In the second washing stage, which now begins, the temperature of water rises rapidly, and the smaller the quantity of water in the container, the more rapidly will the temperature rise. This course of temperature variation is shown in FIGURE 1 by the lines 3, 4, 5. The line 3 corresponds to a quantity of 3 litres in the container, line 4 corresponds to 3.7 litres and line 5 corresponds to 4.4 litres of water all per kilogram of dry material. The consumption of heat energy in the second washing stage is approximately proportional to the heating period, i.e. to the times $t_2 - t_1$, $t_3 - t_1$ and $t_4 - t_1$ in the examples shown.

In the machine shown in FIGURE 2, a setting lever 7 which controls a regulating valve 8a fitted into an inlet pipe 8 leading to the container 13, is actuated by a Bowden cable 6. An overflow device 10 is attached to the Bowden cable 6 by a connecting member 9 so that the overflow 10 is adjustable in height. The arrangement of the Bowden cable is such that as the height of the overflow 10 increases, the through-flow cross-section of the valve 8a for the water inlet decreases and conversely. To actuate the Bowden cable 6, in order to adjust the level to which the container 13 is filled and to adjust the quantity of water constantly flowing in through the valve 8a, a manually operated switch 11 is provided at the front of the washing machine. This switch is combined with a suitable scale 12 with the inscription "low," "medium" and "high," and with it the desired liquid level of the machine and the corresponding quantity of fresh water can be adjusted.

In the embodiment shown, three heating elements 16, 17 and 18 are provided in the container 13. These can be switched on separately or in combination through a switch 14, 15. If the heating time or alternatively only the duration of the second washing stage is to be kept constant. The appropriate number of heating elements can be automatically switched on or off through the switch 14, 15 connected to the Bowden cable 6. In the present case, when the overflow 10 is set at its highest, all three heating elements 16, 17, 18 are switched on.

When the overflow is set at medium height, the elements 16, 17 are switched on, and when the overflow is at its lowest, only the heating element 16 is switched on. It is, however, also possible to control the heating elements 16, 17, 18 by a thermostat.

We claim:

1. In a washing machine, in combination, a housing forming a chamber for a washing liquid, agitating means in said chamber for repeatedly displacing soiled articles in said chamber through the liquid contained therein, inlet means terminating in said chamber for supplying said washing liquid thereto, adjustable-level outlet means in said housing forming an overflow for excess liquid and conducting said excess liquid out of said chamber, said inlet means including an adjustable valve for selectively regulating the rate of flow of said liquid into said chamber, coupling means interconnecting said outlet means and said valve, and manually operable setting means connected with said coupling means for positioning said outlet means to maintain a predetermined substantially constant volume of said liquid in said chamber while concurrently positioning said valve so as to maintain substantially constant the total quantity of water employed to treat said articles at substantially all positions of said outlet means.

2. In a washing machine, in combination, a housing forming a chamber for a washing liquid, agitating means in said chamber for repeatedly displacing soiled articles in said chamber through the liquid contained therein, inlet means terminating in said chamber for supplying said washing liquid thereto, adjustable-level outlet means in said housing forming an overflow for excess liquid and conducting said excess liquid out of said chamber, said inlet means including an adjustable valve for selectively regulating the rate of flow of said liquid into said chamber, coupling means interconnecting said outlet means and said valve, manually operable setting means connected with said coupling means for positioning said outlet means to maintain a predetermined substantially constant volume of said liquid in said chamber while concurrently positioning said valve so as to maintain substantially constant the total quantity of water employed to treat said articles at substantially all positions of said outlet means, and means in said chamber for heating the liquid contained therein.

3. The combination according to claim 2 wherein said heating means comprises circuit means operatively connected with said outlet means for increasing the thermal output of said heating means upon adjustment of said outlet means to increase said predetermined volume of liquid in said chamber.

4. The combination according to claim 3 wherein said heating means includes a plurality of heating elements, said circuit means including switch means for individually and combinatively energizing said elements.

5. The combination according to claim 4 wherein said coupling means comprises a flexible cable interconnecting said outlet means, setting means, valve and switch means.

6. The combination according to claim 2, further comprising indicator means co-operating with said setting means for providing a visual indication of the position of said outlet means.

7. In a washing machine, in combination, a housing forming a chamber for a washing liquid, agitating means in said chamber for displacing soiled articles therein relative to said liquid, variable-flow inlet means terminating in said chamber for supplying said washing liquid thereto, adjustable-level outlet means in said housing forming an overflow for excess liquid and defining the quantity of residual liquid within said chamber, heating means including a plurality of heating elements energizable for heating the washing liquid therein at varying rates, and common control means for said heating means, said inlet means and said outlet means including a manually operable switch element for selectively regulating the rate of flow of said liquid into said chamber in dependence upon

the level of said outlet means and controlling the thermal output of said elements in dependence upon the volume of liquid retained in said chamber.

8. In a washing machine, in combination, a housing forming a chamber for a washing liquid, agitating means in said chamber for displacing soiled articles therein relative to said liquid, variable-flow inlet means terminating in said chamber for supplying said washing liquid thereto, adjustable-level outlet means in said housing forming an overflow for excess liquid and defining the quantity of residual liquid within said chamber, heating means including a plurality of heating elements energizable for heating the washing liquid therein at varying rates, common control means for said heating means, said inlet means and said outlet means including a manually oper-

10

5

able switch element for selectively regulating the rate of flow of said liquid into said chamber in dependence upon

the level of said outlet means and controlling the thermal output of said elements in dependence upon the volume of liquid retained in said chamber, and a visual adjustment scale mounted upon said machine and connected with said control means for indicating the setting thereof.
